METHOD AND MEANS FOR MANIPULATION
OF SOUND RECORDS

George P. Regan and Charles S. Franklin, Los Angeles, Calif., assignors to Regan-Day, Inc., Los Angeles, Calif., a corporation of California

Application April 10, 1936, Serial No. 73,670

21 Claims. (Cl. 179—100.3)

This invention relates to means and methods whereby sound films or other continuous strips or members bearing reproducible sound recordings may be manipulated for various purposes. 5 For example, during editing of sound recordings for use in the reproduction of motion pictures with accompanying sound, it is necessary at times to locate and carefully identify a specific phrase in a long continuous record so that this 10 phrase may be deleted or modified in the final print. No methods are available at present whereby this can be accomplished readily and accurately. Numerous other instances occur where it is highly desirable to control the reproduction 15 of a continuous sound recording and some of these instances will be described in detail herein-after.

Generally stated, the present invention relates to a method whereby a continuous film carrying 20 a plurality of sound modulation groups in spaced sequential alignment thereon may be automatically manipulated in such manner that each one of the sound modulation groups may be reproduced in its entirety and the progress of the film 25 automatically stopped immediately in advance of the reproducing unit. In this manner the continuous film may be caused to be reproduced in a step-by-step progression, each step representing a complete sound modulation group, such as a 30 phrase, word or sound effect. Careful analysis of each phrase, sentence or continuous sound may thus be attained.

The invention also relates to means whereby 35 the method may be carried out in a facile and accurate manner. The device of this invention includes a double pick-up, one of said pick-ups being employed in actually reproducing the sound so that it may be heard and studied, whereas the other pick-up acts as a control and automatically 40 stops the film immediately before a succeeding sound reaches the reproducing unit. This latter or controlling pick-up operates relays which automatically deenergize the means employed in moving the film past the reproducing pick-up. 45 For purposes of simplification, reference will hereinafter be made to strip film and photographic sound records carried thereby, it being understood that the invention is not limited to its use on continuous strip film nor to any particular type of sound recording. Any reproducible sound record may be manipulated in accordance with this invention.

An object of this invention, therefore, is to disclose and provide means for manipulating 50 strip film carrying a plurality of sound records

in spaced succession whereby desired portions may be reproduced automatically.

Another object of the invention is to disclose and provide a method whereby the study, analysis, editing, dubbing and modification of continuous sound recordings may be performed rapidly 5 and accurately.

A further object of the invention is to disclose and provide a novel optical system whereby each and every sound modulation group carried by a 10 continuous film may be reproduced in its entirety without the necessity of reproducing a complete succession of such groups.

Another object is to disclose and provide an electrical relay system whereby the continuous 15 progress of a film bearing a plurality of sound records in spaced succession may be terminated immediately in advance of a succeeding sound record.

These and other objects, modifications, adaptations and various uses of the methods and means of this invention will become apparent to those skilled in the art from the following detailed description of one form of the invention and several modes of operation which can be employed. It 25 is to be understood that the following description is simply illustrative of one embodiment of the invention.

In describing the methods and devices, reference will be made to the appended drawings, in 30 which:

Fig. 1 is a front elevation of a double optical system which may be employed.

Fig. 2 is an enlarged view, partly in section, of the pick-up and marking devices embodied in 35 the apparatus shown in Fig. 1.

Fig. 3 is a vertical transverse section taken along the plane III—III of Fig. 1.

Fig. 4 is a simplified wiring diagram diagrammatically illustrating certain of the elements 40 employed in carrying out the method of the invention.

Fig. 5 is an enlarged view of a modified form of control device which may be embodied in the 45 apparatus shown in Figs. 1, 2, and 3.

Fig. 6 diagrammatically represents a portion of motion picture film adapted for use with the modification of Fig. 5.

In the description given hereinafter, reference 50 will be made to sound records or sound recordings. As stated hereinbefore, the invention does not relate to any particular method of recording or reproducing sound but embraces all known methods of recording and reproduction. Moreover, in the description given hereinafter, ref- 55

erence will be made to groups of modulations. By this term reference will be made to a sequence of modulations impressed upon or photographically or otherwise recorded upon strip film metal, 5 wire, or the like. The term "modulation group" refers to a sequence of modulations representing sound and may include but a single note or a phrase, sentence, or other substantially continuous sequence of sounds. Each modulation 10 group, irrespective of its length or brevity, is spaced from an adjoining group by a "null period" or "space period" during which no sound or modulation exists. Such null period or space period may consist of a period of time ranging 15 from one-twentieth of a second to many minutes. In a single modulation group there may be shorter fractional instants during which no actual modulation exists on the record but because of the shortness of such period the modulation group is 20 not disrupted and to all intents and purposes constitutes a continuous sound.

The method of the invention comprises intermittently moving a strip carrying sound modulation groups in spaced succession past a reproducing unit and stopping the film or strip at points immediately in advance of a succeeding sound modulation group. This is accomplished automatically by the apparatus of this invention and although the device described in detail hereinafter will not recognize null periods or space 25 periods shorter in length than about one-fifth of a second, it is readily apparent that by changing the electrical characteristics of the relay systems embodied in the device that even shorter 30 null periods may be recognized by the device and cause the intermittent movement of the film strip to be terminated whenever such shorter null period appeared. Less selective devices may not 35 recognize null periods which are shorter than 40 one-half or even one second.

In the device shown in the drawings, a continuous film carrying modulation groups in succession on a sound track is fed from a reel 1 in the magazine 2 through the device and rewound 45 upon the reel 3. The film 4 may pass over an idler roller 5 and then into contact with a driven sprocket 6. The film is maintained in contact with such driven sprocket by means of rollers 7.

Thereafter the film passes over rollers 8, 9, 50 and 10 and through a group of rollers indicated at 11 by which it is fed over a drum 12, the drum being also driven. The film then passes over another group of rollers indicated at 13 and over the rollers 14, 15, and 16. It again contacts with 55 the sprocket 6, passes over another spring-tensioned idler roller 17 and is returned to the take-up reel 3 of the magazine 2.

The sprocket roller 6 and the drum 12 are 60 also indicated in the wiring diagram, Fig. 4. The drum 12 is shown in greater detail in Figs. 2 and 3. As there shown, the drum is mounted upon a shaft 18 which is coupled to the shaft 19 of a synchronous motor 20 through an electromagnetic clutch and brake, generally indicated at 21. The interior of the drum 12 is maintained 65 under vacuum, such vacuum being supplied to the interior of the drum through a stationary fitting 22 provided with a rotatable member 23 which forms a tight running fit with the interior surfaces of the drum 12. The conduits 24 and 25 connect the interior of the drum 12 with a source of vacuum such as a vacuum pump operated by the motor 26 (see Fig. 4). The film 4 passes 70 over the surface of the rotatable drum 12 and 75 extends over the forward edge of the drum to

occupy the position indicated in dotted lines at 4' (Fig. 3).

It is to be understood that the surface of the drum 12 is perforated so that the suction or vacuum existing within the drum 12 causes the 5 film 4' to closely adhere to the surface of the drum. For further details, attention is called to Patent No. 2,008,402.

Two pick-up devices are positioned in operative relation to the film passing over the drum 12. A 10 reproducing pick-up is indicated at 28 and a relay or controlling pick-up is indicated at 29. These pick-up devices may be in the form of suitable photoelectric cells capable of receiving light modulated by the record borne by the film 4. For example, the controlling pick-up 29 may receive light from a source 30, the light being directed by means of a telescope or objective lens system 31 through the sound track area of the film while it is occupying the position shown at 4' on the drum 15 20 12, the modulated light being then reflected by means of a prism or similar reflective element 32 upon the controlling pick-up or photoelectric cell 29. The reflective element 32 may be mounted upon a ring or sleeve 34 adjustably positionable 25 about the stationary fitting 22, as by means of the set screws 35. The photoelectric cell 29, light source 30 and lens system 31 may be mounted upon a bracket 36 which is also adjustably positionable as by means of the lock screw 37 operating in the slot 38. The linear spacing along the periphery of the drum 12 of the axes of the optical systems 31 and 32 may thus be varied.

It will be evident that when film is passing through the device in the direction of the arrows, 35 the sound modulation groups carried by the sound track of said film will first pass in operative relation to the control pick-up 29 and then pass over the reproduction pick-up 28.

By referring to Fig. 4, the electrical relationships of the various units will become apparent. The sprocket 6 is driven by means of a variable speed motor indicated at V. S. M., said motor being provided with a resistance in series which may be varied so as to insure a rotational speed substantially equivalent to the rotational speed of the synchronous motor 20 which drives the drum 12. Clutch and brake coils, generally indicated at 40, control the operation of the sprocket 6 and are embodied in an electromagnetic clutch and brake unit interposed between the motor and the sprocket 6. Similar clutch and brake coils 41 are interposed between the motor 20 and the drum 12. A three phase, 220 volt source of current is indicated at 42. The reversing switch S-1 controls the operation of the motor 20. The switch S-2 controls the motor 26 which runs the vacuum pump supplying vacuum to the conduits 24 and 25 and the interior of the drum 12.

The reproducing pick-up 28 converts the light modulated by the sound modulations borne by the film 4 into an oscillatory current which is then sent through a preamplifier 43 and a main amplifier 44 from which the audio currents are sent to a reproducing unit 45, from which they may be heard. The control pick-up 29 converts light modulated by the sound modulations of the film 4 into an oscillatory current which may be sent through a preamplifier 46 and another amplifier 47, which then supplies current to a transformer feeding the grid of a thermionic valve V-1. The variable speed motor V-S-M may be supplied with current such as normal 110 volt D. C. from terminals indicated at 48.

Any suitable arrangement of relays capable of 75

attaining the desired results may be employed but for purposes of illustration the wiring diagram shows a relay system which embodies the relays E, F, G, and M. In starting operations, the variable speed motor is started by closing switch S-3 and the synchronous motor 20 is started by closing the switch S-1. The switch S-2 is also closed so as to operate the vacuum pump. The sprocket 6 and the drum 12 are not rotated, however, since the brake coils are energized due to a locking circuit which is closed by the deenergized relay M.

In order that the film, bearing a plurality of sound modulation groups in spaced succession, be automatically intermittently moved past the reproducing unit 28 and automatically stopped at a point immediately in advance of a succeeding modulation group carried by such film, the relay key is depressed, closing a circuit between the grid of the valve V-2 and the ground, thus removing the C bias and causing an increase in plate current of said tube V-2. This increase is sufficient to energize the relay E. When relay E is energized, the upper or make contacts of the relay close a circuit through the winding of relay M, thus energizing it. The relay M closes a circuit to the clutch solenoids, causing the drum 12 and the sprocket 6 to rotate, moving the film past the control pick-up 29 and the reproducing pick-up 28.

At the time the relay E is energized, the lower make contacts close a locking circuit consisting of the plate of the tube V-2 through the relay E, break contacts of relay F and the filament return circuit. Attention is called to the fact that the relay E is in parallel with the plate supply of the tube V-2 only when relay E contacts are closed and when the locking circuit can be completed through relay F or G.

The general sequence of operations, therefore, which takes place when the relay key is depressed and the circuit closed, consists of the following: relay E is energized, relay M is energized, the brake coils are deenergized and the clutch coils are engaged, relay F is energized and relay G is energized. All these operations consume but a very short period of time. When the relay G is energized, the holding or locking circuit is closed, which keeps relay M and the clutch energized regardless of the variations in energy supply to relays E or F.

As soon as the film starts moving past the pick-ups 29 and 28, a sound modulation group carried by such film will obviously cause oscillatory current or electrical energy to be supplied from the amplifier 47 to the transformer feeding the grid of tube V-1, causing an increase of plate current through the winding of relay F. When F is energized, it tends to open a locking or holding circuit of relay E but this does not occur because normally the relay key is depressed for a longer interval of time than that required for the sequence of operations and while such key is depressed, E continues to be energized. When F is energized due to flow of energy from the amplifier 47 of the control pick-up 29, a circuit through G is closed, causing G to become energized.

The circuit which energizes G includes the lower make contacts of the relay F, the winding of relay F to one pole of the 110 volt line and from the other pole of the 110 volt line through the 14,000 ohm resistor to the contacts of F. When the circuit is closed and G is energized, the holding circuit and relays E, M and the

clutch solenoids will remain energized regardless of whether or not the relay key is depressed. As a result, relays E, M, F, and G remain energized as long as any modulation group is passing the control pick-up 29.

As soon as no modulation group is passing the control pick-up 29 (that is, whenever a null space or period appears on the sound track), relay F is deenergized. When F is deenergized, the locking circuit to relay E is closed through the break contacts. Relay G also deenergizes. As long as a null period is passing the control pick-up 29, the holding circuit is maintained through the break contacts of relay F. In this manner the film is driven past the pick-ups 28 and 29 as long as no modulation group is carried by the film past the control pick-up 29.

As soon as a succeeding modulation group appears on the film in operative relation to the control pick-up 29, relay F is again energized. This immediately breaks the holding circuit to relay E, which in turn opens the circuit to relay M. Relay M opens the clutch circuit, disconnecting the motors from the sprocket 6 and drum 12 and applies energy to the brake coils, bringing sprocket and drum to a quick stop. During this part of the operation, relay G does not close the locking circuit because relay E is deenergized before relay G has had time to operate.

When the drum comes to a stop, reproduction of sound from the track ceases. Relay F is deenergized and the entire system is restored to its initial condition, the various contacts being in the positions indicated in Fig. 4.

It will be evident that in the operation described, a group of modulations has been reproduced and the film moved throughout a complete group of modulations and for a length equivalent to the length of any null or blank period following such group of modulations, the film being stopped with the reproducing pick-up 28 immediately in advance of the beginning of the succeeding group of modulations.

If it is desired to move the film independently without causing the mechanism to automatically stop the film at the beginning of a succeeding modulation group, then the clutch key can be depressed, said clutch key actuating relay M to energize the magnetic clutches and open the circuits and brake coils.

When, during analysis of a film by means of the device described hereinabove, it is desired to mark or identify a particular point on the film or a particular modulation group which is being reproduced, the marker key may be depressed, such marker key energizing a solenoid 50 which causes the marker point 51 to bear against the film carried on the drum 12. Visual means of identifying a particular section is thus provided.

As pointed out hereinbefore, the film is brought up to the desired linear speed almost instantaneously immediately upon engagement of the sprocket 6 and drum 12 with their respective motor drives through the magnetic clutches. The drum 12 is not provided with sprocket teeth which may tear the film but instead holds the film in close contact therewith by reason of the applied vacuum.

As shown in Fig. 1, an appreciable loop of film exists between the sprocket 6 and the drum 12. In the event the sprocket 6 is moved at a slightly lower speed than the drum 12, the loop passing over the rollers 8, 9, 10, etc., will become shortened. Such shortening of the loop will cause the arms

52 and 53 to pivot about the point 54, it being understood that the arms 52 and 53 are rigidly connected around the pivot point and carry the rollers 8, 9, 10, and 14, 15, 16, respectively. A pivotal motion of the arms 52 and 53 as described causes the contact finger 56 to move over a plurality of contact points which vary the resistance interposed in the shunt circuit of the motor, speeding up the variable speed motor. Very 10 gentle film tension on either side of the balance arms will thus cause the contact point 56 to hunt back and forth across a normal point at which the linear speeds of the sprocket 6 and the drum 12 are equal. A balanced condition is eventually 15 reached without any slippage, tearing of the film, or other difficulties.

The method and apparatus of this invention are particularly adapted for the analysis of sounds recorded photographically on film. The 20 double photoelectric cell system in which one cell acts as a controlling element whereas the other reproduces the sound, is a distinctive feature. The provision of means whereby the film may be rapidly (almost instantaneously) brought 25 up to full linear speed and as readily stopped, as by means of the magnetic clutches and brake coils, permits careful and accurate analysis of each phrase, word, sound or other modulation group. Attention is called to the fact that all 30 modulation groups are completely reproduced, that is, no portion of the group is lost during starting or stopping. When it is desired to prepare a cue film for the instruction of foreign artists (as in the preparation of foreign versions), 35 the original or American version may be analyzed in accordance with this method and suitable cue marks applied thereto by means of the marker, switch, solenoid and pencil. Precise instants of initiation and cessation of sound can thus be identified and greatly facilitate subsequent dubbing 40 or translation processes. Moreover, the method and apparatus may be used in selecting a desired portion of a lengthy record whenever such portion has either particularly good or bad characteristics. 45

The apparatus may also be used for rerecording purposes as where several sound effects are to be rerecorded or combined. It may also be used in cutting, editing and like work and may 50 be combined with a viewing machine or projector so that the action as well as the sound may be analyzed.

The method and apparatus may also be used to great advantage in teaching music. The basis 55 of all musical education is repetition, study and familiarity with themes, constructions, passages, etc. Because of its ready manipulation, reversibility, etc., recordings of famous compositions by outstanding artists and/or composers can be 60 reproduced, reversed, repeated, analyzed and studied at leisure. The apparatus may be quickly stopped and reversed by introducing electromagnetic brakes on the motor shafts (separate from the brake coils acting directly on the sprocket and drum shafts) and by providing suitable reversing switches so that reversal to standard linear speed 65 can be attained in a very short interval.

In many dramatic plays and during radio broadcasting programs, it is desirable that various sound effects, incidental music, etc., be supplied at stated intervals. Said sound effects may 70 be carried by a relatively short length of film, the null or blank spaces between sound modulation groups being as short as 1 inch, whereupon, by the 75 operation of this invention, the desired sound

effects may be instantaneously reproduced immediately upon closure of the relay key.

It is to be noted that even though a second sound effect is not to occur for a full minute after the completion of the first, it is not necessary that 5 ninety feet of blank film exist between the two sound effects since the device will automatically stop the film with the reproducing pick-up 28 immediately in advance of the secondary group of modulations. When the proper cue is given 10 on the set or stage, the relay key is depressed and the reproduction of the secondary modulation group is instantaneously initiated.

Instead of employing a control pick-up such as the control pick-up 29, the various sound effects 15 may be carried by a film provided with perforations such as the perforations 60 and 61 shown in the film 59 (Fig. 6), the space between perforations constituting a complete modulation group. Instead of the photoelectric control pick-up 29, a 20 spring contact finger 62 is employed, said contact finger being pivoted as at 63, the end of the spring finger being capable of contacting the drum 12 through a perforation such as the perforation 69. Contact of the finger with the drum 25 closes a control circuit, terminating further progress of the film by reason of a deenergization of the clutch and a simultaneous energization of the brake coils.

When the relay key is operated, however, the 30 film motion is initiated and as long as the finger 62 rides upon the film, it is insulated from the drum. The spring contact finger 62, therefore, acts in a manner very similar to that of the control pick-up in that the machine will stop at 35 definite predetermined places on the film sound record.

Those skilled in the art will appreciate that numerous changes and modifications can be made in the general arrangement and construction of 40 the devices operating in accordance with this invention and that the method of the invention is applicable to numerous uses. All changes, modifications and adaptations coming within the scope 45 of the appended claims are embraced thereby. 45

We claim:

1. In a machine for manipulation of strip film carrying a plurality of sound modulation groups in succeeding spaced relation, the combination of a reproducing pick-up in operative relation 50 to said film; a relay pick-up in advance of said reproducing pick-up, said relay pick-up being adapted to convert sound modulation carried by the strip film into electrical energy; means for driving said strip film past said relay pick-up and 55 recording pick-up in succession; means for energizing said driving means; and a relay system adapted to maintain said driving means operative while a sound modulation group carried by said film is moving past said relay pick-up and 60 during any null period between said modulation group and a succeeding sound modulation group, said relay system being adapted to stop said driving means when a succeeding sound modulation is moved past said relay pick-up. 65

2. In a machine for manipulation of strip film carrying a plurality of sound modulation groups in succeeding spaced relation, the combination of a reproducing pick-up in operative relation to 70 said film; a relay pick-up in advance of said reproducing pick-up; means for driving said strip film past said relay pick-up and reproducing pick-up in succession; means for energizing said driving means; and a relay system adapted to maintain said driving means operative while a sound 75

modulation group carried by said film is moving past said relay pick-up and during any space period between said sound modulation group and a succeeding sound modulation group, said relay system being adapted to stop said driving means when a succeeding sound modulation group is moved past said relay pick-up, said reproducing and relay pick-ups being spaced a distance correlated to the lag of said relay system and driving means whereby said reproducing pick-up is in position to reproduce the succeeding sound modulation group in its entirety upon a succeeding energization of said driving means.

3. In a machine for the manipulation of strip film carrying a plurality of sound modulation groups in succeeding spaced relation, the combination of: a drum adapted to carry strip film, a motor drive for said drum, an electromagnetic clutch and brake element operatively connecting said drum and motor; a reproducing pick-up in operative relation to said film on said drum; a relay pick-up in advance of said reproducing pick-up, and a relay system operatively connected to said relay pick-up, said relay system including a relay adapted to energize said clutch and brake elements in the alternative, and a holding circuit adapted to hold said brake element inoperative until a secondary sound modulation group is in operative position with respect to said controlling relay pick-up.

4. In a machine for the manipulation of strip film carrying a plurality of sound modulation groups in succeeding spaced relation, the combination of: a drum adapted to carry strip film, a vacuum means for retaining film on said drum, a motor drive for said drum, an electromagnetic clutch and brake element operatively connecting said drum and motor; a reproducing pick-up in operative relation to said film on said drum; a relay pick-up in advance of said reproducing pick-up, and a relay system operatively connected to said relay pick-up, said relay system including a relay adapted to energize said clutch and brake elements in the alternative, and a holding circuit adapted to hold said brake element inoperative until a secondary sound modulation group is in operative position with respect to said controlling relay pick-up.

5. In a machine for the manipulation of strip film carrying a plurality of sound modulation groups in succeeding spaced relation, the combination of: a drum adapted to carry strip film, vacuum means for retaining film on said drum, a motor drive for said drum, an electromagnetic clutch and brake element operatively connecting said drum and motor; a reproducing pick-up in operative relation to said film on said drum; a relay pick-up in advance of said reproducing pick-up, and a relay system operably connected to said relay pick-up adapted to maintain said clutch element operative while a sound modulation group carried by said film is moving past said relay pick-up and during any space period between said sound modulation group and a succeeding modulation group, said relay system including a relay energized directly by said controlling relay pick-up, and means for selectively energizing said brake element upon a secondary energization of said directly energized relay by said control relay pick-up.

6. In a machine for manipulating strip film carrying a plurality of sound modulation groups in succeeding spaced relation, the combination of: a drum adapted to carry strip film, a motor drive for said drum, an electromagnetic clutch and

brake element operatively connecting said drum and motor; a sprocket adapted to feed film to and take film from said drum, a motor drive for said sprocket and means operated by film between said sprocket and drum tending to equalize the speed of the sprocket to the speed of the drum.

7. In a machine for manipulating strip film carrying a plurality of sound modulation groups in succeeding spaced relation, the combination of: a drum adapted to carry strip film, a motor drive for said drum, an electromagnetic clutch and brake element operatively connecting said drum and motor; a sprocket adapted to feed film to and take film from said drum, a motor drive for said sprocket and means operated by film between said sprocket and drum tending to equalize the speed of the sprocket to the speed of the drum, a pair of pick-up devices in operative relation to film on said drum, one of said pick-up devices being operably connected with said electromagnetic clutch and brake means for controlling the rotation of said drum.

8. In a machine for manipulation of strip film carrying a plurality of sound modulation groups in succeeding spaced relation, the combination of: a drum adapted to carry strip film, a reproducing pick-up in operative relation to film carried by said drum, and a control pick-up in operative relation to said film in advance of said reproducing pick-up.

9. In a machine for manipulation of strip film carrying a plurality of sound modulation groups in succeeding spaced relation, the combination of: a drum adapted to carry strip film, a reproducing pick-up in operative relation to film carried by said drum, and a control pick-up in operative relation to said film in advance of said reproducing pick-up, and means operated by said control pick-up for controlling the rotation of said drum.

10. In a machine for manipulation of strip film carrying a plurality of sound modulation groups in succeeding spaced relation, the combination of: a drum adapted to carry strip film, a reproducing pick-up in operative relation to film carried by said drum, and a control pick-up in operative relation to said film in advance of said reproducing pick-up, and means for adjustably positioning said control pick-up with respect to said reproducing pick-up.

11. A method of manipulating strip film carrying a plurality of sound modulation groups in spaced succession thereon, comprising intermittently moving the film past a reproducing unit, and automatically stopping the film at points immediately in advance of a succeeding sound modulation group carried by said film.

12. In a method of manipulating strip film carrying a plurality of sound modulation groups in spaced succession thereon, the steps of intermittently moving the film, each period of movement corresponding to the length of film between the beginning of successive sound modulation groups on said film.

13. In a method of manipulating strip film carrying a plurality of sound modulation groups in spaced succession, the steps of intermittently moving the film past a pair of linearly spaced reproducing units, aurally reproducing the sound modulations by the latter of said reproducing units, and controlling the intermittent movement of the film by the first of said units.

14. A method of manipulating strip film carrying a plurality of sound modulation groups in spaced succession thereon, comprising intermittently moving the film past a reproducing unit,

the periods of movement corresponding to the length of film between beginning points of successive modulation groups, automatically stopping the film at points immediately in advance of a successive modulation group carried by said film, and governing the stoppage of the film by means of said modulation groups.

15. In a machine of the character described, the combination of: a drum adapted to carry strip film, a motor drive for said drum, an electromagnetic clutch and brake element operatively connecting said drum and motor; a sprocket adapted to feed film and take film from said drum, a motor drive for said sprocket and means operated by film between said sprocket and drum tending to equalize the speed of the sprocket to the speed of the drum, said last named film-operated means comprising a pair of arms connected to each other and pivotally mounted near said point of connection, and rollers carried by said arms and in engagement with film between said sprocket and drum.

16. In a machine of the character described, the combination of: a drum adapted to carry strip film, a motor drive for said drum, an electromagnetic clutch and brake element operatively connecting said drum and motor; a sprocket adapted to feed film and take film from said drum, variable speed motor means for driving the sprocket, and variable resistance means for changing the speed of said variable speed motor, said variable resistance means being operated by changes in film tension on feed and take-up sides of said drum.

35 17. In a machine of the character described, the combination of: a drum adapted to carry strip film, a motor drive for said drum, an electromagnetic clutch and brake element operatively connecting said drum and motor; a sprocket adapted to feed film and take film from said drum, variable speed motor means for driving the sprocket, variable resistance means for changing the speed of said variable speed motor, said variable resistance means being operated by a pair of arms connected to each other and pivotally mounted near said point of connection, and rollers carried by said arms and in engagement with film between said sprocket and drum.

18. In a machine of the character described, the combination of: a drum adapted to carry strip film, a motor drive for said drum, an electromagnetic clutch and brake element operatively connecting said drum and motor; a sprocket adapted to feed film to and take film from said drum, a motor drive for said sprocket and means operated by film between said sprocket and drum tending to equalize the speed of the sprocket to the speed of the drum; a reproducing pick-up in operative relation to said film on said drum; a relay pick-up in advance of said reproducing pick-up, and a relay system operatively connected to said relay pick-up, said relay system including a relay adapted to energize said clutch and brake

elements in the alternative, and a holding circuit adapted to hold said brake element inoperative until a secondary sound modulation group is in operative position with respect to said controlling relay pick-up.

19. In a machine of the character described, the combination of: a drum adapted to carry strip film, vacuum means for retaining film on said drum, a motor drive for said drum, an electromagnetic clutch and brake element operatively connecting said drum and motor; a reproducing pick-up in operative relation to said film on said drum; a relay pick-up in advance of said reproducing pick-up, means for adjustably positioning one of said pick-ups with respect to the other, and a relay system operatively connected to said relay pick-up, said relay system including a relay adapted to energize said clutch and brake elements in the alternative, and a holding circuit adapted to hold said brake element inoperative until a secondary sound modulation group is in operative position with respect to said controlling relay pick-up.

20. In a device of the character described, the combination of a hollow rotatable drum adapted to carry strip film, means for rotating said drum; a pick-up device in operative relation to film on said drum, said device including a light source, lens system and a responsive cell exteriorly of the drum and a reflective member positioned within the periphery of said drum; a second pick-up device in operative relation to said drum and including an adjustable base carrying a light source, lens system and light responsive cell and an adjustably positionable reflective member within the periphery of said drum; said pick-up devices being in spaced linear relation with respect to film on the drum, and means operated by one of said pick-up devices for controlling the rotation of said drum.

21. In a device of the character described, the combination of: a hollow rotatable drum adapted to carry strip film, means for rotating said drum, an end closure for said drum, means for supplying vacuum to said drum; ports in the face of said drum whereby vacuum may be applied to film carried thereon; a pick-up device in operative relation to film on said drum, said device including a light source, lens system and a responsive cell exteriorly of the drum and a reflective member positioned within the periphery of said drum; a second pick-up device in operative relation to said drum and including an adjustable base carrying a light source, lens system and light responsive cell and an adjustably positionable reflective member within the periphery of said drum; said pick-up devices being in spaced linear relation with respect to film on the drum; and means operated by one of said pick-ups for controlling the rotation of said drum.
